VENTILATOR PANEL FOR WINDOWS

Willis Levi Manning, Madison, Wis., assignor, by
mesne assignments, to C. F. Burgess Labora-
tories, Inc., Madison, Wis., a corporation of
Delaware

Application November 5, 1931, Serial No. 573,097

9 Claims. (Cl. 98—99)

This invention relates to improvements in venti-
tilator panels for windows. Such panels are fitted
into window frames below the lower sashes, for
example, and have an opening therein communi-
cating with the outer air to permit ventilation
through said opening when the window in other
respects is closed. Among other uses said opening
may constitute the intake for a duct leading to a
power ventilator of the semi-portable type used
10 in homes, offices, churches, schools and other
buildings.

It is an object of the invention to provide a ven-
tilator panel which is simple and easy to install
in any type of double hung window and which can
15 be adjusted readily in any width of window frame
and make a sufficiently tight fit therein to prevent
substantial leakage of air around the same.

It is another object of the invention to provide
a device of this character which is inconspicuous,
20 which does not require the driving of any nails or
screws into the window casing, or which does not
require the defacing of the casing in any way and
which can be taken from the window and moved
25 to another window in the same room or in another
room either in the same building or in another
building without damage and without requiring
renewal of parts.

Further objects will become apparent as the
description is read in connection with the accom-
30 panying drawings in which one embodiment of
the invention is illustrated.

Fig. 1 is a perspective view of a window and ven-
tilator with the panel installed beneath the lower
sash.

Fig. 2 is an enlarged central section of the lower
half of the window.

Fig. 3 is a perspective view of the panel.

Fig. 4 is an enlarged elevation thereof including
the lower part of the window sash.

Fig. 5 is an enlarged partial elevation of an end
section of the same panel.

Fig. 6 is an enlarged partial elevation of the
middle section thereof.

Fig. 7 is a section on the line 7—7 of Fig. 6.

Fig. 8 is a section on the line 8—8 of Fig. 6.

Fig. 9 is a section on the line 9—9 of Fig. 5.

Fig. 10 is a section on the line 10—10 of Fig. 5.

Fig. 11 is a perspective view of an enlarged de-
tail.

Fig. 12 is a section on a horizontal plane of an-
other detail.

The panel in its commercial form consists of
three sections fitted together between the window
sill and lower sash rail of a double hung window
55 and partially overlapping the inner vertical sur-

face of said sash rail. It comprises a central sec-
tion or duct connector section 11, and two end
sections 12 and 13. Filler sections may be used
if these are necessary. All these sections, when
installed in a window or other opening are mitered
60 together in abutting end-to-end relation to form
an apparently continuous interior facing as shown
in Fig. 1.

The duct connector section 11 is made of a shal-
low channel or other suitably shaped section 14,
65 this shallow channel also being typical of the end
and other filler sections. The legs 15 and 16 of
the channel point outward (out of the window) so
that the plane vertical surface of the convex side
of the channel is the one seen by the occupants
70 of the room. The bottom leg 16 rests on the win-
dow sill 17. The outer edge of the bottom leg 16
is bent downwardly as shown at 18 and rests
against the outer vertical edge of said sill to pre-
vent inward movement and also to make a good
75 seal. Sash 19 closes down adjacent the edge of
upper leg 15 and is prevented from scraping
against this edge by means of a strip of felt 20
or other yielding or resilient material which pre-
vents substantial leakage of air and furthermore
80 provides a dust proof and sound proof joint. This
resilient material is mounted in the slot formed
by upper leg 21 of channel 22 mounted slightly
beneath leg 15, the two channels 22 and 14 being
held together by welding or otherwise fastening
85 the same. See Fig. 7. Leg 21 preferably should
be slightly shorter than leg 15. The lower leg 23
of channel 22, which runs the entire length of
duct connector section 11 and extends slightly
90 beyond both ends thereof, also acts as a stop for
sash 19 and prevents lowering the same too far.
Channel 22 also stiffens channel 14. Adjustable
guides 24 for sash 19 preferably are provided as
shown, one at each end of section 11. Said guides
95 are adjustable to the thickness of the lower sash
rail having slots therein through which pass
screws 25 mounted in plate 26.

The duct connector section 11 has an opening
27 in it with a suitable frame 28 for making a con-
nection with the intake duct of a ventilator here-
100 inafter referred to. A visor 29 attached to lower
leg 23 of channel 22 (Figs. 2 and 8) is also pro-
vided over opening 27 so that rain and snow do
not enter it. A mortise 30 (Fig. 8) is provided
at the lower part of each of the two ends of the
concave side of the channel 14 to make con-
nection with the tenon of the adjoining end
section or filler section if it is needed. Said
mortise is formed by welding steel strip 31 in place
105 as shown, spaced from the back of the channel to
110

leave opening 30. The tenon is formed on the abutting channel section 12 or 13 by welding a short length of channel section 32 against the back thereof and which projects from the end 5 thereof as shown in Fig. 5, so that it will fit snugly but slide easily in said opening 30.

The end sections 12 and 13, having adjustable telescoping end pieces are made right and left hand respectively so that they may be used at 10 opposite ends of the duct connector section 11. Therefore only one section will be described as both are alike in construction and action and furthermore one adjustable end section is sufficient for practical purposes, although two are 15 preferable. The facing (Fig. 10) is a shallow channel 33 of the same height and contour as channel 14 used in duct connector section 11 and against which it abuts. It has upper leg 34 and lower leg 35 with dependent portion 36. A number 20 of such channels are provided varying in length by one inch increments so that by proper selection any width of window may be fitted, the adjustable telescopic end piece hereinafter described being adapted to be extended to fill in any opening less than one inch long. A clip for a 25 felt strip 37 is made by welding an angle 38 slightly below leg 34. The adjustable telescopic end piece comprises short channel section 39 at the end of section 12 opposite tenon 32. This end 30 piece fits telescopically and slidably in the concave side of channel 33 (Figs. 5 and 9). A limited adjustment of the end piece with respect to channel 33 is permitted by slots 40 in channel 33 cooperating with screws 41 in channel 39. Said 35 screws, when tightened, lock the adjustable end piece in place after proper adjustment is made.

When the composite panel is installed in a window, the approximately correct length is obtained by using end sections of such length that 40 said panel may be fitted between the inner stop beads 42 of the window frame. The final fit is obtained by pulling out the adjustable end pieces until the vertical end of channel 39 abuts against the stop beads 42 (Fig. 12). Screws 41 are then 45 tightened.

Since the channel 39 fits telescopically in the concave side of section 33, the slight break in the continuous appearance is hardly noticeable at an end of the connector close to the window frame. 50 An angle 43 extending the full width of channel 39 is welded to the concave side thereof, close to and parallel to the upper leg thereof to form a slot for holding a strip of felt 44 or other resilient material, as described in connection with the other portion of the section. The felt used 55 is installed preferably after the window connector is installed and usually is made continuous across the entire connector instead of providing separate pieces for each section. It has been found unnecessary to support the felt where it spans the small gap left between angles 38 and 43 (Fig. 5) resulting from the adjustment of the telescopic end piece. The felt strip contacting with the interior surface of the lower sash rail prevents 60 leakage of air regardless of whether said sash rail is in its lowermost position against the stop which limits its downward movement, as shown in Fig. 2, or whether it is somewhat higher, as long as it is not raised high enough to clear said felt strip. 65

70 Channel 39, as shown in Figs. 3, 9 and 10, also has attached to it, at right angles to its outer end, an offset adjustable channel 45. This is of such size that the legs thereof fit into the sash groove 46 as shown in Figs. 2 and 12. Leg 47 of adjustable channel 45 is formed by attaching an angle

to the end of channel 39 or by forming it as a part of the end of the leg of angle 43 as shown. Although leg 47 is of the same length vertically as the balance of adjustable channel 45, the other portion of the angle at a right angle to leg 47, is preferably of the same height (top to bottom) as channel 39 (see Fig. 3). The base of the channel consists of overlapping plates 48, 48', the latter being welded to the angle 47. Plate 48 is bent to form the other leg 49 of said adjustable channel 45. These angles 47, 49 have their upper ends at the same level as plate 26 of guide 24 or lower leg 23 of channel 22 since the lower edge of sash 19 contacts with it. The slots 50 in the angular continuation 48 of leg 49 allow it to be slidably adjustable on screws 51 in web 48' so that channel 45 may be made of varying widths and leg 49 will abut against parting strip 52. When the end of channel 39 abuts against stop 42, the legs 47 and 49 of channel 45 enter sash groove 46 to thereby prevent lateral movement and securely hold the end of the window connector in place, after screws 41 and 51 are tightened. Since the legs of the adjustable channel 45 project into sash groove 46, it is necessary to have some end adjustment of 100 said panel or it becomes impossible to install it properly without removing stop bead 42. Such adjustment is provided by the telescopic end portion heretofore described.

When only one adjustable end piece is employed, attached to the end of one of the end sections, the other end section has an adjustable channel attached directly thereto at right angles, similar to those previously described. Thus the length of the panel, as a whole, is varied by adjusting one end only, for the small amount necessary.

The end-to-end channel joints are sealed by the tenon 32 and the overlapping projecting ends of channel 22. Furthermore, the lower sash rail 115 19 closes down over the upper portion of the channel and tends to prevent the entrance of rain, snow, dust, dirt and noise through the vertical joints between the channel ends.

Filler sections may be used in addition to the 120 duct connector and end sections. Such filler sections have the construction of that portion of the end section away from the telescopic end piece. They are tenoned at one end to make connection with the mortise of the duct connector 125 section and mortised at the other to receive the tenon of the end section.

After the window connector is installed, the lower sash is open a certain amount so that an opening is left between the window pane 55 of the upper sash (Fig. 2) and the top rail 56 of the lower sash, and also between the window pane of the lower sash and the lower rail of the top sash. This allows air and noise to enter. A seal is therefore provided to close one of these two 130 openings, preferably the upper one. It consists of composite angle 57 made by welding two of the legs of two angles together as shown in Fig. 11, leaving a slot between the other two legs in which a piece of felt 58 or other resilient material is mounted and then held by pinching the legs together. On the top of the upper of said legs any suitable number of adjustable clamps 59 are mounted, as by welding. Each clamp consists of a steel sheet welded to angle 57 and having two of its edges 60 turned back on themselves as shown to form guides for a tongue 61, the projecting end 62 of which is turned down at right angles, to form one jaw of the clamp, as shown in the drawings. A portion 63 of the metal

is punched out of the other end and turned up at right angles, leaving a slot 64, an opening being provided in said turned up portion. An angle 65 is welded to the sheet below tongue 61 and is disposed in the slot 64 as shown. Angle 65 has a threaded opening to register with said other opening in portion 63. A long screw 66 which may be a thumb screw or one with a screw driver slot, is in threaded engagement with both holes 10 and when turned causes slidable member 61 to be adjusted back and forth in its guides. The top rail of sash 56 is gripped between angle 57 and leg 62 of slidable member 61 as screw 66 draws the slidable member in. When the screw is tightened the seal is held firmly in place. Felt 58 is in contact with window pane 55 of the upper sash and provides a wind, dust and noise proof joint therewith. The construction shown also allows for a considerable variation in thickness of the 20 top of sash 56. The construction is simple, effective and is hardly noticeable from the room, especially if the parts thereof are of the same finish as the sash.

The frame 28 on the middle section of the 25 panel is open at the bottom as shown in Figs. 2 and 8 and is arranged to fit over the flanged end 67 of duct 68 as shown also in Fig. 4. Thus before the panel is installed in the window it may be slipped down over said flanged end to lock the 30 parts together and after said panel is installed in position, the window sill 17 prevents said duct from moving downwardly to disengage it from the side members of the frame or guides to which it is slidably fitted. The duct is preferably held 35 in position slightly above the window sill to clear the same as for example by an angle iron 69 or other suitable support.

Although the ventilator panel is shown mounted in the lower part of the window frame, it may, 40 under certain conditions of use, be mounted in the upper part thereof.

I claim:

1. A window ventilator panel adapted to be installed between the sill and the interior surface 45 of the lower rail of a partially open lower sash of a window, comprising abutting sections mortised together in end-to-end relation and forming an apparently continuous interior facing, said sections comprising a duct connector section and two end sections, each of said end sections having a telescoping adjustable end piece with a section at right angles thereto adapted to fit in the sash groove, said interior facing sections and said adjustable end piece being located inside 50 the plane of the inside surface of said sash rail to allow the bottom edge of said sash rail to drop below the top edge of said panel, and resilient means along the exterior top portion of said panel adapted to contact with the inside surface 55 of said sash rail.

2. A window ventilator panel adapted to be installed between the sill and the interior surface of the lower rail of a partially open lower sash of a window, comprising abutting shallow channel sections mortised together in end-to-end relation, the legs of said channels pointing outwardly, the interior surfaces of said abutting channel sections forming an apparently continuous interior facing, said sections comprising a duct connector section and two end sections, each of said end sections comprising a telescoping adjustable end piece with an adjustable channel section at right angles thereto with the legs thereof adapted to fit in the sash groove, said first channel section and said adjustable end piece

being located inside the plane of the inside surface of said sash rail to allow the bottom edge of said sash rail to drop below the top edge of said panel, a stop and a guide for said sash rail on the exterior portion of said panel, resilient means along the exterior top edge of said connector adapted to contact with the inside surface of said sash rail, and means depending from the outer edge of the bottom leg of said channel sections adapted to contact with the outer edge of said sill. 80

3. A window ventilator panel adapted to be installed between the window frame and the interior surface of a sash rail of a partially open window sash, comprising abutting sections mortised together in end-to-end relation and forming an apparently continuous interior facing, said sections comprising a duct connector section and two end sections, each of said end sections having a lateral attachment to fit in the sash groove, 90 and resilient means along the exterior of said panel adapted to contact with the inside surface of said sash rail and maintain a substantially airtight joint in various different positions of adjustment of said sash rail vertically. 95

4. A window ventilator panel comprising panel sections mortised together in abutting end-to-end relation between the window sill and the interior surface of the lower rail of a partially open lower sash of a window and forming an apparently continuous interior facing, said sections comprising one having an opening therein and a plurality of end sections, at least one of said end sections having a longitudinally adjustable end piece abutting the interior sash bead, said end 100 piece having exteriorly offset legs extending into the sash groove, means for sealing the joint between said lower sash rail and said panel comprising a strip of flexible material mounted along the top exterior portion of said panel and bearing against the interior surface of said sash rail, means for maintaining said sealing means under pressure comprising a guide member projecting exteriorly from said panel and engaging the exterior side of said sash rail. 105

5. A window ventilator comprising a vertical panel with its base resting on the window sill and spaced inwardly from the vertical plane of the interior surface of the lower sash rail, rearwardly extending means near the top of said 115 panel to engage said interior surface of said sash rail and prevent leakage of air thereby and a stop extending rearwardly from said panel, below said first means, to limit the downward movement of said sash rail. 120

6. A window ventilator comprising a vertical panel with its base resting on the window sill, spaced inwardly from the inner plane of the lower sash rail and having rearwardly extending end portions fitting into the sash grooves 125 to hold it in place, yielding means extending rearwardly from near the top of said panel to engage the interior surface of said sash rail to prevent leakage of air thereby, a stop extending rearwardly from said panel below said resilient 130 means to limit the downward movement of said sash rail, said panel having an opening therein and a duct extending inwardly from said opening. 135

7. A window ventilator comprising a vertical panel with its base resting on the window sill, spaced inwardly from the inner plane of the lower sash rail and having rearwardly extending end portions fitting into the sash grooves to hold it in place, yielding means extending rearwardly 145 to it in place, yielding means extending rearwardly 150

from near the top of said panel to engage the interior surface of said sash rail to prevent leakage of air thereby, a stop extending rearwardly from said panel below said resilient means to limit the downward movement of said sash rail, said panel having an opening therein, a hollow frame at the sides and top of said opening and a duct having flanges fitting into said hollow frame.

8. A window ventilator comprising a vertical panel with its base resting on the window sill, spaced inwardly from the inner plane of the lower sash rail and having rearwardly extending end portions fitting into the sash grooves to hold it in place, yielding means extending rearwardly from near the top of said panel to engage the interior surface of said sash rail to prevent leakage of air thereby, a stop extending rearwardly from said panel below said resilient means to limit the downward movement of said sash rail, said panel having an opening therein, guides at the sides of said opening and a substantially horizontal duct having outwardly turned flanges

to fit said guides to provide slidable engagement between the same.

9. A window ventilator comprising a vertical panel with its base resting on the window sill, spaced inwardly from the inner plane of the lower sash rail and having rearwardly extending end portions fitting into the sash grooves to hold it in place, yielding means extending rearwardly from near the top of said panel to engage the interior surface of said sash rail to prevent leakage of air thereby, a stop extending rearwardly from said panel below said resilient means to limit the downward movement of said sash rail, said panel having an opening therein, grooved members at the top and sides of said opening, a substantially horizontal duct having lateral flanges at the top and sides thereof to fit into said grooved members whereby said duct may be slipped into place from below, before said panel is installed, said window sill preventing downward movement of said duct after installation thereof whereby it is locked to said panel.
